The ornamental designs for passive infra-red sensor, as shown and described.

DESCRIPTION

FIG. 1 is a front view;

FIG. 2 is a rear view;

FIG. 3 is a right-side view;

FIG. 4 is a left-side view;

FIG. 5 is a bottom view;

FIG. 6 is a top view;

FIG. 7 is an isometric view; and,

FIG. 8 is an isometric view.

FIG.2

FIG.1

FIG.4

FIG.3

FIG. 6

FIG. 5

FIG.8

FIG.7
